UNITED STATES PATENT OFFICE.

MAX L. LIPSON, OF DETROIT, MICHIGAN.

COMBINED GLOVE AND MITTEN.

1,404,398.

Specification of Letters Patent. Patented Jan. 24, 1922.

Application filed April 18, 1921. Serial No. 462,281.

To all whom it may concern:

Be it known that I, MAX L. LIPSON, a citizen of the United States, and resident of Detroit, in the county of Wayne and State of Michigan, have invented a new and useful Combined Glove and Mitten, of which the following is a specification.

This invention relates to a combined glove and mitten, and is designed to embody the 10 desirable features of both types of hand-coverings.

The superior warmth of mittens over gloves is well known, and the former are used in cold weather by chauffeurs and others engaged in outdoor occupations. The warmth of the mitten is due to the fact that the side-pieces of each finger of the glove are eliminated, thus reducing the radiating surface almost by half. Also, the portion of 20 the mitten which receives the fingers has uninterrupted communication with the portion which receives the palm of the hand, and the greater warmth of the palm can freely radiate to the fingers. This is not the case in a 25 glove where each finger of the glove is a separate pocket fitting the respective finger of the hand rather closely, and allowing no passage for the radiated warmth.

The mitten has not hitherto been more 30 widely used by the general public owing to its clumsy appearance. The present invention has for its object the construction of a combined glove and mitten, which shall have the appearance of the former and the greater 35 warmth and utility of the latter.

Other features and advantages will hereinafter appear.

In the accompanying drawings:

Fig. 1 is a cross-section of the glove shown 40 in Fig. 2, the section being taken on the line 1—1 of Fig. 2 and shown somewhat enlarged.

Fig. 2 is a front elevation of the combined glove and mitten embodying the invention.

Referring to the drawings, there is shown 45 a glove comprising a thumb-portion 1 for receiving the thumb of the hand, a finger-portion 2 for receiving the remaining fingers of the hand, and the remainder of the glove 50 comprising the usual palm- or body-portion 3 for receiving the remaining portions of the hand usually covered by a glove of this type. The thumb-portion and body-portion are of the usual construction and substantially the 55 same as in the ordinary glove or mitten.

The finger-portion 2 however, differs ma-

terially from either of these two well-known types of gloves. This portion comprises individual finger members 4, 5, 6, and 7, the length of these members corresponding to 60 the length of the fingers of the hand which they are to receive, as in the ordinary glove. However, instead of each finger comprising top, bottom, and side-pieces as in the usual glove, the index-finger 4 and the fifth finger 65 7 have no interior side-pieces, and the members 5 and 6 have no side-pieces. All of the members have top-pieces 10, 11, 12, and 13, and bottom-pieces 14, 15, 16, and 17. All adjacent top-pieces are connected by webs 21, 70 22, and 23, connecting top-pieces 10 and 11, 11 and 12, and 12 and 13, respectively. All adjacent bottom-pieces are connected by similar webs 24, 25, and 26, connecting bottom-pieces 14 and 15, 15 and 16, and 16 and 75 17, respectively.

From the above description in connection with the drawings, it will be apparent that the receptacles for the fingers of the hand are similar to those of an ordinary glove and 80 that by eliminating the side-pieces of the ordinary glove-fingers, a continuous pocket is formed for the four fingers of the hand other than the thumb, said pocket being a continuation of the body-portion of the 85 hand.

It will be understood that the combined glove and mitten illustrated may be stitched in any well-known manner. It is to be understood also that the glove may be stitched 90 or otherwise reinforced at the joints of the finger-members or at the meeting line of the fingers and the body-portion to facilitate bending at these points, these being well-known expedients in the art.

Various changes and modifications may be made within the scope of the annexed claims.

Having now particularly described my invention, what I claim and desire to secure by Letters Patent is:

1. In a combined glove and mitten, a thumb portion for the thumb of a hand, a finger portion for the remaining fingers of the hand, and means whereby said finger portion is subdivided into individual finger-members for receiving the respective fingers of the hand, said members being connected to form a continuous, uninterrupted passage between the finger-members.

2. In a combined glove and mitten, a thumb portion for the thumb of a hand, a finger portion for the remaining fingers of the hand,

a body portion, and means whereby said finger portion is subdivided into individual finger-members for receiving the respective fingers of the hand, said members being connected to form a continuous, uninterrupted passage between the finger-members and between the finger portion and the body portion.

3. In a combined glove and mitten, a thumb-portion for the thumb of a hand, and a finger-portion for the remaining fingers of the hand, said finger-portion comprising individual finger-members, each of said members having a top-piece and a bottom-piece, and the adjacent pieces of said members being joined to form a continuous, uninterrupted passage between the finger-members.

4. In a combined glove and mitten, a thumb portion for the thumb of a hand, a finger-portion for the remaining fingers of the hand, said finger-portion comprising individual finger-members, each of said members having a top-piece and a bottom-piece, and web inserts connecting adjacent top-pieces and bottom-pieces to form a continuous, uninterrupted passage between the finger-members.

5. In a combined glove and mitten, a thumb-portion for the thumb of a hand, and a finger-portion for the remaining fingers of the hand, said finger-portion comprising a top section and a bottom section, said sections being joined at their peripheries, said top section comprising top pieces, said bottom section comprising bottom-pieces, said top and bottom-pieces cooperating to form individual finger-members corresponding to

the fingers of the hand other than the thumb, the adjacent top-pieces and adjacent bottom-pieces being joined to form a continuous, uninterrupted passage between the finger-members.

6. In a combined glove and mitten, a thumb-portion for the thumb of a hand, a finger-portion for the remaining fingers of the hand, said finger-portion comprising a top section and a bottom section, said sections being joined at their peripheries, said top section comprising top-pieces, said bottom section comprising bottom-pieces, said top and bottom-pieces cooperating to form individual finger-members corresponding to the fingers of the hand other than the thumb, and a web interposed between each pair of adjacent top-pieces and each pair of adjacent bottom-pieces whereby said pieces are joined together to form a continuous, uninterrupted passage between the finger-members.

7. In a combined glove and mitten, a thumb portion for the thumb of a hand, a finger portion for the remaining fingers of the hand, and means whereby said finger portion is subdivided into individual finger-members for receiving the respective fingers of the hand, said members being connected to form a continuous, uninterrupted passage between the finger-members, the lengths of said members corresponding to the lengths of the respective fingers of the hand.

Signed at Detroit in the county of Wayne and State of Michigan this 7th day of April, A. D. 1921.

MAX L. LIPSON.
